UNITED STATES PATENT OFFICE.

JULIUS H. GUGLER AND MARTIN LINDEM, OF MILWAUKEE, WISCONSIN; SAID LINDEM
ASSIGNOR TO SAID GUGLER.

REGULATING-SWITCH FOR STORAGE BATTERIES.

1,123,275.

Specification of Letters Patent.

Patented Jan. 5, 1915.

Application filed November 11, 1911. Serial No. 659,695.

To all whom it may concern:

Be it known that we, JULIUS H. GUGLER and MARTIN LINDEM, both of Milwaukee, Wisconsin, have invented a Regulating-Switch for Storage Batteries, of which the following is a specification.

This invention relates to storage batteries, and more particularly a means for controlling the end-cells, which are used for regulating the electric potential in charging and discharging the batteries. As is well-known regulating-switches have to be provided for cutting in and out successive end-cells of the battery in order to keep it constant according as its condition of charge varies, and on account of the resistance of the battery a slightly higher voltage is necessary in charging than in discharging.

It is the object of our invention to provide means for facilitating this operation, and particularly for regulating the charging of the end-cells, whereby they shall not be over-worked relatively to the rest of the battery.

A further object of the invention is to combine in a single switch functions of two or three ordinary switches.

The principle of our invention consists in disposing two or sometimes three contact-arms to operate on a single series of contact-pieces, to which the several end-cells of the battery are respectively connected, said contact-arms, or two of them where three are employed, being connected respectively with the charging and discharging circuits.

Another feature of our invention consists in providing means for limiting the movement of one of said arms with respect to another.

Our invention may be embodied in a great many forms, of which several have been illustrated more or less schematically in the accompanying drawings, wherein—

Figure 1 shows the simplest form of my apparatus, providing merely for two independent contact-arms on the same set of contact pieces; Fig. 2 shows a form in which one of the contact-arms is limited in its movements on both sides of the other; Fig. 3 shows a form in which one of the arms is limited with respect to the other in one direction only; Fig. 4 is a cross-section on the plane 4 of Fig. 3 to illustrate a detail of construction; Fig. 5 shows a construction similar to that of Fig. 3, with the exception that the limit for the discharging arm is

spaced at two end-cells behind the charging arm; Fig. 6 shows an alternative form in which our apparatus may be constructed, providing for two arms which work on different sets of contact-pieces, but upon the same center, and are limited with respect to each other; Fig. 7 shows a regulating-switch having three contact-arms, together with a mode of connecting the same which provides for the use of a booster-dynamo for the end cells; Fig. 8 shows in front view the details of a mechanical construction for interlocking the two arms with respect to one another in various positions; Fig. 9 shows a longitudinal section of said construction; Fig. 10 is a front view of a three-arm construction as shown in Fig. 7 having the detail arrangement of the arms shown in Figs. 8 and 9, and Fig. 11 is a longitudinal section of said construction with the three arms in alinement.

The reference letters refer each to the same part in each figure of the drawings.

Considering first the form of apparatus shown in Fig. 1, G may designate the prime source of current, usually a dynamo and hereinafter termed the generator, B the storage-battery provided with a number of movable end-cells b, and L the service-circuit, in which are represented for the sake of illustration lamps 1. The generator, battery and lamp-circuit are all connected together at one pole, viz: the right-hand end, as shown in Fig. 1, by leads 11, 12 and 13. They are interconnected at their other poles by means of the regulating-switch, which forms the subject of this invention, and which comprises two arms C and D, turning upon a single pivot at E and making electrical contact with any of a series of contact-pieces A, disposed concentrically around said pivot as shown, and connected to the respective end-cells b by leads 14. The arms are insulated from each other at the pivot as indicated by the insulation e. One of said arms C, which may be called the charging-arm, is connected with the free pole of the generator G by a lead 15, and the other D, which may be called the discharging-arm, with the free pole of the lamp-circuit L by a lead 16, and each arm may be provided with a suitable handle c, d, the arm C being prolonged beyond its pivot, to enable said handle to be applied without interfering with the relative movement of the two arms, these

being independent in this case. While the charging-arm will usually be kept some cells in advance of the discharging-arm, yet this arrangement enables the operator to set the 5 arms to include any number of cells in both the charging and discharging-circuits, each independently of the other. Stop-pins are placed at *a* to limit the movements of the arms to the arc of contact.

10 Fig. 2 shows a switch similar in general form to that of Fig. 1, provided with the two arms *C'*, *D'*, turning about the pivot *E'*, and making contact with the contact-pieces *A'* (the connections in this case being omitted, as they are the same as before); but in 15 this case the arm *D'* is limited to a position two cells in advance of the arm *C'*, and three cells in arrear thereof; said limitation being provided by any of various known mechanical means, such for example as the shifting-handle *d'*, disposed upon one side of a flattened extension *d²* on the arm *D'*, which strikes against the side of the arm *C'* in one 20 limiting-position, and an insulated pin *d³* 25 on the other side, which strikes against the side of the arm *C'* in the other limiting-position, as shown by the dotted-line position of the arm *D'*; this prevents too great or too 30 small a number of end-cells from being used for charging, which are not used in discharging.

In Fig. 3 the arrangements are substantially the same as in Fig. 1, as indicated by the reference letters, with the exception that 35 for the two arms *C* and *D* are substituted arms *C²*, *D²*; the latter being limited in its advance movement to the position occupied by the arm *C²*, whereby it is provided that no end-cell shall at any time be used for 40 discharging which is not also being charged. This may be accomplished by means of a 45 goose-neck *d⁴* applied to one side of the arm *D²*, and extending over the body thereof, and having the shifting-handle *d⁵* on the 50 end thereof; this arrangement is convenient, because it keeps the shifting-handle in the center of the arm. Insulation *d⁶* is of course provided at the point where the goose-neck *d⁴* abuts upon the arm *c²* to prevent electrical communication.

In Fig. 5 the same construction is used except as regards the limiting position of the discharging with respect to the charging-arm. The two arms are here designated 55 *C³*, *D³*, provided with shifting-handles *c'*, *d'*. On one side of the arm *D³*, and offset from the center line thereof by the requisite space, is an insulated-pin *d⁸* adapted to abut upon the side of the arm *C³*, and prevent the 60 advance of the arm *D³* beyond a position two end-cells in arrears of the latter, thus leaving always at least this number of extra cells which are being charged. In some cases it may be desirable to preserve this 65 relation between the two arms constantly

during ordinary operation, and for this purpose, we may provide a locking-piece or catch *c²* mounted on a pin *c³*, and adapted to engage upon the pin *d⁸*, and retain the same; so that it is necessary in regulating 70 the voltage to move only one of the handles *c'*, *d'*.

In Fig. 6 in place of a single series of contact-pieces *A*, we provide two series *A²*, *A³* arranged concentrically about a single 75 pivot *E'*, and two arms *C⁴*, *D⁴* turning on said pivot and insulated from each other as shown, said arms making contact with the respective sets of contact-pieces; one of said arms has a rearward extension *c⁴*, carrying 80 an insulated stop-pin *c⁵*, which striking against the side of the arm *D⁴* limits the position of the latter to one end-cell in arrear of its own position; of course, by shifting the position of the pin *c⁵* any other 85 limiting relation between the two arms may be provided for. Semicircular metal contact arcs *F*, *G* are here shown to provide means for connecting the respective arms with the generator and discharge-circuits 90 respectively by means of the leads 15 and 16; and a stop-pin *H* is placed so as to limit the movements of the two arms to their respective semicircular arcs. As will be seen by the connecting-leads 17, the diametrically opposite contact-pieces *A²* and *A³* of 95 each set are connected together in pairs, and both to the respective end-cells *b* by leads 18.

In Fig. 7 we have shown how our improved regulating-switch may be used for 100 booster-regulation of the end-cells. In this case we have provided three arms *I*, *J* and *K* insulated from each other upon the pivot *E²* as shown, and making contact with the contact-pieces *A* as before, said contact-pieces being connected as in Fig. 1 to the 105 end-cells *b* of the battery *B*. According to this mode of operation, the generator *G* is permanently connected to the lighting-circuit *L*, as is also the fixed end of the battery; and that pole of the generator and discharge-circuit which is not connected to the fixed pole of the battery is connected by the lead 19 to the arm *I* as shown, so as to 110 keep the effective voltage of the battery *B* constant with respect to the generator and discharge-circuit. The other two arms *J* and *K* are connected respectively by leads 115 21 and 20 to the terminals of a dynamo *M* of low voltage and large current, commonly called a booster, which serves to bring the end-cells up to voltage independently, and this can be done by shifting the arms *J* and *K*. The shifting-handles *j* and *k* thereof must be of course so placed as not to interfere with the movements of the arm *I*. To prevent the short-circuiting of the booster the movements of the arms *J* and *K* are relatively so limited that they cannot approach nearer to each other than two con- 120 125 130

tact-spaces, this being accomplished by an insulated lug k' on the side of one arm, which strikes a projection j' on the side of the other; the dotted-line position of the 5 arm K indicates the limiting-position of the two arms.

In some cases it may be found desirable to work the two arms in fixed relation, say 10 one or two end-cells apart from each other, with provision of means for varying the number of differential end-cells, or varying the fixed relation. This may be accomplished by the mechanical arrangements 15 shown in Figs. 8 and 9. The two arms C^5 and D^5 , shown in these figures, may represent any of the arms shown in the preceding 20 figures. The arms are shown as mounted upon an insulating-slab N, which carries also the contact-pieces A. A bearing-box O 25 is secured in a hole in the slab N by means of screws o, one of which provided with an extra nut o' serves as a terminal for making 30 electrical connection to the arm C^5 . This arm has a tubular-journal c^6 , which turns in the bearing-box O, and within this journal is mounted a post P insulated therefrom by insulating collars p, and having its front 35 end shaped as a pivot-pin for the arm D^5 . The two arms may be provided with suitable 40 means for making good electrical contact with the pieces A, such for example as carbon blocks c^7 , d^9 , seated in sockets in the ends of the arms, and pressed against the 45 contact-pieces by springs c^8 , d^{10} . The arm 50 D^5 is provided with a shifting-handle d^{11} , and on the opposite side of the pivot with a flanged-lug d^{12} , to which is secured in an 55 insulated manner an arc-shaped piece Q provided on its periphery with a series of 60 notches q corresponding in their positions to the spacing of the contact-pieces A. The arm C^5 is provided with an extension c^9 beyond the pivot, and this extension carries a housing c^{10} , which acts as a bearing for 65 a radially reciprocating bolt R, the end of which is pressed toward the arc Q, and into the notches thereof, by means of a spring r' contained in the housing c^{10} . 70 On the end of the extension c^9 is a bearing and a pivot-pin s', upon which is mounted in a pivotal manner a shifting-handle S, which is connected by links s² to the end of the bolt R. The bolt R normally enters 75 one of the notches q, and locks the arm C^5 fast in the desired relation to the arm D^5 , so that in shifting the discharging-arm, the 80 charging-arm will be shifted with it to the requisite extent. To change the relative position of the arm C^5 , the handle S is tilted 85 backward to the dotted-line position of Fig. 9, and then the arm shifted thereby to the desired position, and the bolt R dropped into the corresponding notch. A lug q' limits the movement of the charging-arm in 90 one direction, as shown.

The same construction as that shown in Figs. 7 and 8 can be readily applied to the three-arm construction of Fig. 7 by simply adding the extra arm thereto. In this case the three arms are designated I', J' and K', 70 corresponding with the arms I, J, and K of Fig. 7, respectively, and the wiring shown is the same as in that figure. The contact-pieces A are mounted upon an insulating base N'. The shortest arm K' is provided 75 with the tubular journal k' the same as the journal c^6 in Fig. 9, turning in the bearing-box O', which is secured to the base-plate N' by screws o², one of which has an extra nut o³ for making the electrical connection 80 of the arm k' to the wire 20. Similarly the arm J' has a tubular sleeve j^2 passing through the sleeve k' and carrying on its end a nut j^3 for making connection with the wire 21, said sleeve being insulated from the 85 sleeve k' by insulating collars j^4 .

The outermost arm I' is mounted on the central pin P', which passes through the sleeve j^2 and is insulated therefrom by the collars p, carrying on its end a nut p' for 90 making connections with the wire 19. The uppermost arms i' and J' have handles i' and j' mounted thereon, and the three arms are shown as provided with carbon blocks i⁵ and j⁵ and k⁵ which are pressed against the 95 contact-pieces A by springs i⁶, j⁶, and k⁶.

The arm J', which corresponds to the arm D^5 of Figs. 8 and 9, has its rear end extended and has mounted thereon, but insulated therefrom, a notched segment Q', similar to the segment 100 Q; with this engages the tooth of a reciprocating bolt R', similar to the bolt R and pressed toward the arc Q' and into the notch thereof by means of a spring r², contained in the housing h⁷ which is formed on the 105 rearward extension h⁸ of the lever K', in the same manner as the housing c¹⁰ on the extension c⁹. The shifting-handle S pivoted at s' and connected by the links s² to the end of the bolt R' are the same as in Figs. 8 110 and 9, operating in the same manner. The lug q² is provided to limit the movement of the charging arm in one direction, as before.

From the above description it will be readily seen that our invention is not limited 115 to special forms and mechanical constructions such as we have hereinabove shown by way of illustration, but that the principles thereof are expressible in a variety of ways as will be well understood by those 120 skilled in the art; therefore the scope of our claims is to be interpreted in view of such alternative construction.

Having thus described our invention, what we claim as new and desire to secure by Letters Patent is:

1. A regulating-switch for storage-battery circuits comprising a set of contact-pieces adapted to be severally connected to the end-cells of the storage-battery, and a 130

- plurality of electrically insulated members adapted to move over said contact-pieces independently, one of which is adapted to be connected to one pole of the charging-circuit, and the other to one pole of the discharging-circuit, the position of one of said members being limited in one direction only with respect to the position of the other, whereby one of said members cannot be shifted beyond its limiting position in one direction without shifting the other also with it but can be shifted independently in the other direction. 5
2. In a storage-battery system of distribution, a battery, a generator and a discharge-circuit connected together at one pole of each, the battery being provided with a plurality of end-cells; in combination with a regulating-switch having a set of contact-pieces with which said end-cells are respectively connected, and two movable members adapted to make contact with said contact-pieces, and one of which is connected to the free pole of said generator, and the other to 10 the free pole of said discharge-circuit. 15
3. In a storage-battery system of distribution, a battery, a generator and a discharge-circuit connected together at one pole of each, the battery being provided with a plurality of end-cells; in combination with a regulating-switch having a set of contact-pieces with which said end-cells are respectively connected, and two movable members adapted to make contact with said contact-pieces, and one of which is connected to the free pole of said generator, and the other to 20 the free pole of said discharge-circuit; one of said members being limited in position with respect to the other, whereby it cannot 25 advance beyond its limiting position without carrying the other with it. 30
4. A regulating-switch for storage-battery circuits comprising a plurality of arms insulated from each other, a row of contact-pieces with which all of said arms make contact, said contact-pieces being adapted to be connected to the respective end-cells of the storage-battery, one of said arms being limited in its movements with respect to an- 35 other arm and means for locking two of said arms in a fixed relative position. 40
5. A regulating-switch for storage-battery circuits comprising a plurality of arms insulated from each other, and a row of contact-pieces with which all of said arms make contact, said contact-pieces being 45
- adapted to be connected to the respective end-cells of the storage-battery, and means for locking one of said arms fast to another arm in successive relative positions with respect thereto, which are separated by the angle between successive contact-pieces. 50
6. In a regulating-switch, the combination of two contact-arms concentrically mounted upon a pivot and insulated from each other, contact-pieces disposed concentrically about said pivot with which they make contact, an arc mounted on one of said arms and having a plurality of notches corresponding in spacing to that of the contact-pieces, a reciprocating-bolt mounted on the other arm and adapted to enter any of said notches, means normally maintaining said bolt in the notches, and a shifting-handle pivotally mounted on said second arm and 55 connected with said bolt, whereby the latter may be withdrawn, and the arm shifted to a different position. 60
7. In a regulating-switch for storage-battery circuits, the combination of a set of contact-pieces adapted to be respectively connected to the several movable end-cells of the battery, and three contact-members guided to move over and make contact with said contact-pieces; two of said members 70 being limited in position with respect to one another, and the third being independent of the other two. 75
8. In a storage-battery regulating-system, a generator, a discharge-circuit, and a battery having a plurality of movable end-cells, one pole of each being connected together; in combination with a regulating-switch having a set of contact-pieces, to which said end-cells are respectively connected, and three contact-arms moving over and making contact with said contact-pieces; one of said contact-arms being independent in its movements of the other two and connected to the free pole of said generator and of said discharge-system; and a booster-dynamo having its opposite poles connected to the other two contact-arms, said contact-arms being limited in position 80 with respect to one another. 90
9. In witness whereof we have hereunto set our hands in the presence of two witnesses. 95
